UNITED STATES PATENT OFFICE.

ADELBERT E. FOUTCH, OF NEW YORK, N. Y., ASSIGNOR TO JAMES M. DAVIS,
OF SAME PLACE.

DESIGN FOR A CASE.

SPECIFICATION forming part of Design No. 28,308, dated February 22, 1898.

Application filed October 29, 1897. Serial No. 656,845. Term of patent 14 years.

To all whom it may concern:

Be it known that I, ADELBERT E. FOUTCH, of New York city, in the county and State of New York, have invented and produced a new and original Design for Cases, of which the following is a full, clear, and exact description.

Reference is to be had to the accompanying drawings, forming a part of this specification, in which—

Figure 1 is a perspective view of a case embodying the features of my design and showing the case closed. Fig. 2 is a perspective view showing the case open.

The leading features of the design will appear from the following description.

The design consists in a structure formed of a body A and a cover B, jointly presenting

the appearance of a plurality of superposed books, and the body and cover having their point of connection at the backs of the books. Interiorly the case presents partitions C, ranging in a direction transverse to the plane of the cover.

The design is adapted to cases which contain stereoscopic goods, such as the stereoscopic glass and the pictures. The stereoscopic goods contained within the cases are there represented as a library.

I claim—

The design for a case, herein shown and described.

ADELBERT E. FOUTCH.
